UNITED STATES PATENT OFFICE.

HYMAN LEVINE, OF DENVER, COLORADO, ASSIGNOR TO INGERSOLL-RAND COMPANY, OF JERSEY CITY, NEW JERSEY, A CORPORATION OF NEW JERSEY.

FLUID-ACTUATED ENGINE.

Application filed October 19, 1925, Serial No. 63,249.

This invention relates to fluid actuated engines, but more particularly to that type of engine in which there are provided a pair of fluid actuated pistons, one reciprocating within the other and at right angles thereto, both pistons cooperating to produce a rotary motion of a crank.

It is an object of this invention to produce equal efficiencies in the running of the engine in either direction of rotation. This object is accomplished by the invention in its improved form by providing exhaust ports arranged symmetrically with respect to the inlet ports in the cylinder head and a reversing throttle valve which is adapted to connect either set of ports with the supply of motive fluid to actuate the engine in the desired direction of rotation.

Other objects and advantages of the invention will be in part obvious and in part pointed out hereinafter.

The invention will be more clearly understood by reference to the following description taken in conjunction with the accompanying drawings, in which

Figure 1 is an end elevation of the engine with the cylinder head removed,

Figure 2 is a vertical section of the engine along the line 2-2 of Figure 1 looking in the direction of the arrows,

Figure 3 is a horizontal section of the engine taken along the line 3-3 looking in the direction of the arrows,

Figure 4 is a view of a portion of the front cylinder head showing the arrangement of inlet and exhaust ports therein, and

Figures 5, 6, 7 and 8 are diagrammatic representations of the cylinder and pistons at important points in the cycle of operations.

Referring to the drawings and more particularly to Figures 1 to 4 inclusive, the engine comprises a cylinder A having a back head B and front head C between which a frame piston D is adapted to reciprocate. A rotary piston E is adapted to reciprocate within the frame piston D and to be guided thereby and is adapted to rotate with respect to a crank pin F to which it is attached. A suitable anti-friction bearing G may be provided between the crank pin F and the rotary piston E. It will be seen that as the frame piston D reciprocates within the cylinder A and as the rotary piston recipro-

cates within the frame piston D, a rotary motion is imparted by the two pistons to the crank pin F causing rotation of the crank shaft H. As is usual in engines of this type, the faces of the frame piston D and rotary piston E sliding on the faces of the cylinder heads B and C are sufficiently tight to prevent substantial leakage of motive fluid from one end of the cylinder A to another.

The rotary motion of the piston E with respect to the cylinder head C affords a means for effecting the admission and exhaust of motive fluid to and from the cylinder to actuate the pistons D and E. To this end there are provided a set of ports J in the cylinder head preferably rectangular in section which lead from a chamber K in the cylinder head C to the inner face of the cylinder head C. The ports J are arranged symmetrically about the rectangular axes of the cylinder head C with respect to a second set of ports L of the same general form as the ports J and which lead from a second chamber O to the inner face of the cylinder head C.

In order to conduct motive fluid from the ports J or L to the pressure faces of the pistons D and E, there are provided distributing ports P in the rotary piston E preferably located on the rectangular axes of the rotary piston E which lead from the face of the rotary piston E to passages Q in the interior of the rotary piston E communicating with the pressure faces of the pistons D and E. In order to admit motive fluid to the pressure face of the frame piston D, passages R cut through the ends of that piston communicate with the passages Q in the rotary piston.

The direction of rotation of the motor depends upon which of the chambers K or O is associated with the supply of motive fluid or exhaust. If the motor is to operate in a clockwise direction (Figure 1), the chamber K should be associated with the supply of motive fluid and the chamber O with atmosphere and vice versa.

This is shown more clearly in Figures 5, 6, 7 and 8 in which the cycle of operations is shown when the engine is rotating counter-clockwise. Only such of the ports as are important with respect to the admission and exhaust of motive fluid to the upper pressure face of the piston E are shown.

The remaining ports are omitted since they cooperate in a similar manner to admit motive fluid to the pressure ends of the pistons with which they cooperate. In Figure 5, the 5 piston E is at its upper end of its stroke and the port P due to the rotary motion of the piston E with respect to the cylinder head C is about to register with the port L which in this instance is associated with the supply of motive fluid. Motive fluid is therefore admitted from the chamber O through the port L in the cylinder head and port P in the piston E and passage Q to fill the chamber in the cylinder adjacent the upper 10 pressure face of the piston E. Rotation proceeds in a counter-clockwise direction to a position at bottom dead center as shown in Figure 7 passing through the intermediate stage of full port opening as shown in 15 Figure 6. From bottom dead center to top dead center the distributing port P is in registry with the port J which acts in this case as an exhaust port as shown in Figure 8. The ports L and J may be spaced from 20 each other a slight distance so that near top dead center the port P will be blanked by the face of the cylinder head C to permit a slight compression before the admission of 25 motive fluid occurs.

30 If the ports J are associated with the supply of motive fluid so as to act as admission ports and the ports L to act as exhaust ports, rotation of the engine will then be clockwise and the cooperation of 35 the ports L and J with the distributing port P will be the reverse of that above described.

In order to reverse the direction of flow 40 of motive fluid within the engine there is a reversing throttle valve S associated with the motive fluid supply pipe T and exhaust pipe U. The functions of the throttle valve S is to reverse the connection of the supply pipes T and the exhaust pipe U with the 45 chambers K and O. In this instance a spool type valve is employed which is adapted to be reciprocated in a valve chest V preferably formed integrally with the cylinder head C and adapted to be moved by 50 means of suitable pinions W engaging a rack X on the end of the valve S. The valve chest V is provided with a grooved port Y continuously communicating with a source of supply pipes T which is controlled by the central flange Z of the valve S. Two 55 ring grooves b and d are formed in the valve chest communicating with the chambers O and K respectively. The central flange Z controls communication between the ring groove d and the groove Y which 60 is associated with the motive fluid supply and an exhaust grooved port e associated with the exhaust pipe U. When the valve is at left position, as shown in Figure 3, 65 exhaust fluid is permitted to escape from the chamber K through the groove d past

the central flange Z into the exhaust groove e and thence to atmosphere. When the valve is moved to the right, motive fluid is permitted to enter from the groove Y past the central flange Z into the chamber K. An end flange f is provided on the valve S to control the ring groove b. Thus, when the valve is at the left, as shown in Figure 3, motive fluid may enter from the ring groove Y past the flange f through the groove b into the chamber O. When the valve is thrown to the right, communication between the supply and the ring groove b is cut off and at the same time a second end flange g at the end of the valve S opposite the flange f opens communication between the exhaust pipe U through the groove e and a groove h connected by a passage (not shown) with the ring groove b whereby exhaust fluid may then flow from the chamber O to atmosphere.

It will be seen that the efficiency of the engine is substantially the same regardless of the direction of rotation since the admission and exhaust ports for each pressure face of each piston are similarly arranged and operates similarly regardless of direction of rotation.

I claim:

1. A fluid actuated engine comprising a cylinder, a reciprocating piston within the cylinder, a rotary piston reciprocating within the reciprocating piston, a head for said cylinder, a set of distributing ports in said rotary piston, a set of ports in said cylinder head adapted to cooperate with said distributing ports, and a second set of ports in said cylinder head similar in location and form to the first set of ports in said cylinder head, and means for connecting either of said sets of ports in said cylinder head with a source of motive fluid supply or with exhaust to determine the direction of rotation of said engine.

2. A fluid actuated engine comprising a cylinder, a reciprocating piston within said cylinder, a rotary piston adapted to reciprocate within said reciprocating piston, a head for said cylinder, a set of distributing ports in said rotary piston, a set of ports in said cylinder head adapted to cooperate with said distributing ports, and a second set of ports similarly located to said first set of ports in said cylinder head with respect to the rectangular axes of the cylinder head, and means for connecting either of said sets of ports in said cylinder head with a source of motive fluid supply or with exhaust to determine the direction of rotation of said engine.

3. A fluid actuated engine comprising a cylinder, a reciprocating piston within the said cylinder, a rotary piston adapted to reciprocate within said reciprocating piston, a set of distributing ports in said rotary

piston; two sets of ports in said cylinder head adapted to cooperate with the distributing ports in said rotary piston, both of said sets of ports in said cylinder head being adapted to operate as admission or

being adapted to control the admission and exhaust of motive fluid to and from said cylinder. 10

In testimony whereof I have signed this specification.

HYMAN LEVINE.
